UNITED STATES PATENT OFFICE

OSCAR STEIN, OF NEW YORK, N. Y.

TOY DEVICE.

1,048,600.

Specification of Letters Patent. Patented Dec. 31, 1912.

Application filed September 30, 1912. Serial No. 723,003.

To all whom it may concern:

Be it known that I, OSCAR STEIN, a citizen of Austria, and residing at Bronx, in the county of New York and State of New York, have invented certain new and useful Improvements in Toy Devices, of which the following is a specification, such as will enable those skilled in the art to which it appertains to make and use the same.

10 This invention relates to toy devices, and the object thereof is to provide an improved device of this class designed to amuse both old and young; a further object being to provide an improvement on a device of this 15 class on which Letters Patent were granted to Erazm Komar, March 14, 1911, No. 986,578, and the invention described and claimed herein is fully disclosed in the following specification of which the accompanying 20 drawing forms a part, in which the separate parts of my improvement are designated by suitable reference characters in each of the views, and in which;

Figure 1 is a side view of my improved toy 25 device;—Fig. 2 a similar view on an enlarged scale with part of the construction shown in section and one part detached from another;—Fig. 3 a plan view of the main or handle portion of my improved toy, and 30 Fig. 4 a bottom plan view thereof.

My improved toy device comprises a main or handle portion *a* constructed and provided, as hereinafter described, and a flying member *b* detachable from the main or 35 handle portion.

The main or handle portion *a* comprises a body *a*² preferably cylindrical in form and preferably composed of wood or other fibrous material and provided with a central 40 longitudinal bore *a*³ and with top and bottom plates *c* and *d* which are secured thereto by screws or in any other way, and the top and bottom plates *c* and *d* are provided respectively with central apertures *c*² and *d*² 45 which communicate with the central bore *a*³ and which are preferably of less diameter than said bore. Mounted centrally in the bore *a*³ of the body *a*² is a shaft *e* composed of top and bottom parts *e*² and *e*³, one of 50 said parts being provided with a reduced extension *e*⁸ which fits in a corresponding socket in the other part and is rotatable therein, or on which said other part is rotatable.

55 The bottom part *e*³ of the shaft *e* is provided with a cylindrical head *e*⁴ which fits

in and is rotatable in the aperture *d*² in the plate *d*, and said head is provided with a transverse plate *e*⁵ the inner edge of which bears on the plate *d* and operates in connection with raised and inclined lugs *d*³ on the plate *d*, the inclinations of said lugs being in the same direction.

The outer end portion of the part *e*² of the shaft *e* is provided with a collar *e*⁶ which fits in the aperture *c*² of the plate *c* and is rotatable therein, and said part of said shaft is provided with an extension *e*⁷ which projects from the body *e*² and on which is mounted a ratchet wheel *f* which is secured thereto, and which may be integral with the collar *e*⁶, and pivoted to the plate *c* at *g* is a pawl *h* having a radial arm *h*² provided with a finger or thumb piece *h*³ which projects parallel with the body *a*² and between which and said body is placed a spring *g* which is preferably secured to said finger or thumb piece and which normally holds the pawl *h* in operative connection with the ratchet wheel *f*.

80 The extension *e*⁷ of the part *e*² of the shaft *e* is tubular in form and is provided in the end thereof with oppositely arranged and spirally formed recesses *i* forming oppositely arranged shoulders *i*² which face in opposite directions, and the flying member *b* is provided with a stud pin *j* adapted to be inserted into the end of said extension *e*⁷ of the shaft member *e*² and said stud pin is provided with a transverse stop pin *j*² adapted 85 to operate in connection with the recesses *i* and shoulders *i*².

The flying member *b* comprises a body portion *b*² preferably made in the form of, or to represent a bird, and said body portion 90 is provided with radial wings *b*³.

Wound on the shaft *e* is a spiral spring *k* one end of which is secured to the part *e*² of said shaft at *k*², and the other end of which is secured to the part *e*³ of said shaft at *k*⁴, and as will be seen the plates *c* and *d* form bearings for the opposite end portions of the shaft *e*, and said opposite end portions of the shaft *e* are longitudinally movable one upon the other, but the spring *k* holds said parts of said shaft in proper relative position and this feature also permits of the winding up of the spring, the part *e*³ of said shaft having a slight longitudinal movement to permit of the cross plate *e*⁵ passing over the lugs *d*³.

110 The operation will be readily understood

from the foregoing description when taken in connection with the following statement thereof. The pawl *h* normally holds the part *e*² of the shaft *e* against rotation in 5 one direction and by turning the head *e*⁴ of the part *e*³ to the right, said part *e*³ of said shaft will also be turned to the right and the spring *k* will be wound up, and when this operation is fully performed, the 10 lugs *d*³ prevent the backward rotation of the part *e*³ of said shaft. The stud shaft *j* of the flying member is inserted into the end *e*⁷ of the part *e*² of the shaft *e*, the ends of the stop pin *j*² entering the recesses *i* and 15 bearing on the shoulders *i*². With the parts in this position, the thumb or finger piece *h*³ of the pawl may be forced inwardly and said pawl released from the ratchet wheel *j* when the spring *k* will rapidly rotate the 20 part *e*² of the shaft *e* so as to throw off the flying member *b*, the wings *b*³ of which are inclined in opposite directions, and said flying member will be projected into space and at the same time rapidly rotate and will 25 soar in the manner of other devices of this class.

My invention is not limited to any particular form of the flying member or the body portion thereof, and while said body portion, as shown, is designed to represent a bird, the same may be made of any form 30 or to represent any object or thing.

Having fully described my invention, what I claim as new and desire to secure by 35 Letters Patent, is;—

1. A toy device comprising a main part or handle member and a detachable flying member, the main part or handle member being composed of a body portion having a 40 central longitudinal bore through which is passed a shaft composed of two parts rotatively connected, the separate parts of said shaft being provided with bearings at the ends of the body portion, a spiral spring wound on the said shaft within said body 45 portion and the ends of which are connected with the separate parts of said shaft, one end of said shaft being projected from the

body portion and provided with a ratchet wheel, a spring operated pawl device connected with the body portion and operating in connection with said ratchet wheel, the other end of said shaft and corresponding end of the body portion being provided with means whereby said spring may be wound 50 up and the end of said shaft which projects from the body portion being tubular in form and provided with opposite spiral recesses forming shoulders, and the flying member being provided with a stud pin adapted to 55 be inserted into the projecting end of said shaft and having a transverse stop pin operating in connection with said recess and shoulders.

2. In a toy device of the class described, 65 a body portion having a central longitudinal bore, a rotatable shaft mounted therein and composed of two rotatably connected parts, a spiral spring wound on said shaft and connected with each of said parts, means at 70 one end of said shaft for winding up said spring, the other end of said shaft being provided with a ratchet wheel, a spring pawl operating in connection with said ratchet wheel, and a flying member adapted 75 to be detachably connected with said end of said shaft.

3. In a toy device of the class described, a body portion having a central longitudinal bore and a shaft passing longitudinally 80 therethrough, said shaft being composed of two parts rotatively connected, and a spiral spring wound on said shaft and one end of which is connected with one part thereof and the opposite end with the other part, 85 said parts of said shaft being also longitudinally movable one upon the other.

In testimony that I claim the foregoing as my invention I have signed my name in presence of the subscribing witnesses this 90 25th day of September 1912.

OSCAR STEIN.
